UNITED STATES PATENT OFFICE

151,202

DESIGN FOR A CIGARETTE LIGHTER

Raymond Wolanske, North Tonawanda, N. Y.,
 assignor to Hygrade Industries, Inc., Buffalo,
 N. Y., a corporation of New York

Application February 15, 1946, Serial No. 126,598

Term of patent 7 years

(Cl. D48—27)

To all whom it may concern:

Be it known that I, Raymond Wolanske, a citizen of the United States, residing at North Tonawanda, in the county of Niagara and State of New York, have invented a new, original, and ornamental Design for Cigarette Lighters, of which the following is a specification, reference being had to the accompanying drawing, forming part thereof.

Figure 1 is a perspective view of a cigarette lighter embodying my new design.
 Figure 2 is a side elevation thereof.
 Figure 3 is a rear elevation thereof.
 Figure 4 is a top plan view thereof.
 Figure 5 is a bottom plan view thereof.

The characterizing features of my design for cigarette lighter resides in the inset portion of the casing with the striker wheel located therein and the cover portion projecting over the edge thereof, all as shown.

I claim:

The ornamental design for a cigarette lighter as shown and described.

RAYMOND WOLANSKE.
